UNITED STATES PATENT OFFICE

ALBERT H. TAYLOR, OF WASHINGTON, DISTRICT OF COLUMBIA, ASSIGNOR, BY MESNE ASSIGNMENTS, TO FEDERAL TELEGRAPH COMPANY, A CORPORATION OF CALIFORNIA

AMPLIFYING SYSTEM

Application filed November 7, 1927. Serial No. 231,591.

My invention relates broadly to an amplification system and more particularly to high power high frequency amplifier circuits.

One of the objects of my invention is to provide a circuit arrangement for high power high frequency power amplifier systems wherein a balanced distribution of power through the amplifier circuit is obtained.

Another object of my invention is to provide a balanced high frequency system for high power amplification wherein inter-grid and inter-plate oscillations are prevented.

Other objects of my invention reside in the amplifier circuit arrangements described in the specification hereinafter following by reference to the accompanying drawings in which:

Figure 1 shows the circuit arrangement of my invention as applied to the coupling system between adjacent stages of a high frequency power amplifier system; Fig. 2 is a modified balanced amplifier circuit arranged according to my invention; and Fig. 3 is a further modified form of the circuit of my invention.

Fig. 1 shows at the left a tube 1 whose plate circuit is provided with modified series tuning according to my invention for coupling with the circuits of tube 2. The diagram shows two tubes arranged in cascade but it will be understood that a multiplicity of tubes can be operated in parallel provided the usual precautions are taken to prevent inter-grid and inter-plate frequency oscillations from occurring. The condenser 3 is a stopping condenser of relatively large capacity, and in the circuits herein described can be neglected as far as its influence on the tuning of the circuit is concerned. The condenser 4 may therefore be considered as directly in parallel with the plate filament capacity, whereas the condenser 5 is the series tuning condenser with respect to the plate circuit inductance 6. The positioning of condenser 5 at the ground potential side has certain distinct advantages, although it necessitates a particular method of exciting the grid of the succeeding tube 2 shown on the right of Fig. 1 and a particular method of balancing or neutralizing between the two tubes.

An analysis of the electromotive forces in the circuit will make this clear. If the radio frequency current through the condenser 5 and coil system 6 is assumed as the basis of phase and the filaments 1a and 2a considered to be at ground potential E_0 , it will be seen that the voltage E_1 across the condenser 5 is 90° behind the current and is inversely proportional at a given frequency to the value of the capacity 5. On the other hand, the voltage across that portion of the coil system 6 in active use, which has been split into two parts E_2 and E_4 , is 90° ahead of the current, and therefore in opposition to the voltage E_1 . The voltage E_3 is equal to the vector sum of the voltages E_1 , E_2 and E_4 . On account of the opposition between the voltage E_1 and the voltages E_2 and E_4 , there will be some point on the coil system 6 which will be a node, and which will therefore, also have the potential E_0 . At this point E_1 becomes equal and opposite to E_2 . To get the necessary exciting voltage on the grid of the amplifier tube which follows the tube 2 on the left, whose circuits we are discussing, it is therefore necessary, contrary to usual practice, to bring the excitation tap well up to the top of the coil system as shown at 10 in Figure 1. There is an alternative, but this will be discussed later in connection with Figure 2. This node can actually be found by the use of a Neon tube or voltmeter and the distribution of potential in the coil system is found to be exactly as described. Now, in order to balance this tube against the tube which follows it, it is necessary to connect the plate 2b of the succeeding tube through a balance condenser 7 and connection 9 to some point whose potential is opposite in phase to the potential supplied to the grid, and having a suitable value. Such a point will be found on the portion of the coil system below the nodal point E_0 . All points below E_0 have a potential opposite in phase to that of the grid potential of the following tube 2, but to get the right amount of balancing potential it may, in some cases, be necessary to extend the coil 6 as shown in Fig. 1, so that the balancing tap may be brought on to turns which are below the point where the condenser 5 is connected.

to the coil system. The manner of exciting the grid of the following tube 2 requires the tap to be put well up into the coil system 6.

Fig. 2 shows an alternative method of exciting the grid 2c and balancing it, which for some high power high frequency circuits has advantages. Here the voltage E_1 is used for excitation purposes to the grid of the following tube 2, the circuit connection 10 being adjacent one end of the inductance 6. A similar analysis of the voltages in the system holds for this circuit, from which it is clear that the balance tap must be put above the nodal point E_0 . The connection 9 including condenser 7 extends from plate 2b to a point on coil 6 above the nodal point.

Fig. 3 shows a variation of the method of Fig. 2 wherein the condenser 5 is replaced by two condensers in series at 11 and 12, the excitation tap 10 for the grid 2c of the following tube 2 being placed at their junction at 14. By shifting the values of 11 and 12 more or less voltage may be directed onto the grid 2c of the following tube 2. This is a capacity potentiometer which gives control of excitation on the grid 2c of the following tube 2 without having to shift taps in the coil system 6. Here again it is necessary to put the balance tap 9 connecting the plate of the following tube at a point above the nodal point E_0 . Condenser C_1 is an impedance condenser, that is, it serves the purpose of adjusting the external and internal impedances of the tube for best efficiency. It should be understood also that the coil system 6 itself is capable of variation so that a suitable amount of inductance can be put in not only to tune in properly the desired frequency supplied to the grid of the left-hand tube 2 but to tune it in such a way as to give a good efficiency. It is to be understood that these circuits are particularly valuable at high frequencies and at high power.

The capacitative reactances constituted by the condensers 11 and 12 are simultaneously adjustable for varying the grid excitation and locating and positioning the node of the current in the output circuit intermediate the ends of the inductance 6 for securing the desired balanced operation of the amplification circuits.

The circuit arrangement of my invention has been found to be very desirable for high power long distant radio telegraphic signaling on short waves.

While I have described preferred embodiments of my invention, I desire that it be understood that modifications may be made and that no limitations are intended other than are imposed by the scope of the appended claims.

What I claim as new and desire to secure by Letters Patent of the United States is as follows:

65. 1. A high power amplification system for

high frequency currents comprising a pair of electron tubes with the output circuit of one electron tube arranged to transfer energy to the input circuit of a succeeding electron tube, an inductance common to said output and input circuits, a pair of capacitative reactances disposed in series with said inductance in said output circuit and each variable to locate and position a node of the voltage in said output circuit intermediate the ends of said inductance and a connection between said capacitative reactances to the grid electrode of the succeeding electron tube for effecting excitation of the succeeding tube from a position below the nodal point of said inductance, while securing balanced operation of said circuits from a position above the nodal point in said inductance.

2. In a high power amplification system for high frequency currents, a plurality of stages of amplification each constituted by electron tubes, means coupling the output circuit of one electron tube with the input circuit of the succeeding electron tube comprising an inductance and a pair of variable condensers disposed in series, said condensers being simultaneously adjustable for locating and positioning a node of the output voltage intermediate the ends of said inductance, a connection common to each of said variable condensers between said variable condensers and the grid electrode of the succeeding electron tube, a balanced circuit connected with the output circuit of the succeeding electron tube and a point in said inductance above the node, said variable condensers being simultaneously adjustable for locating and positioning the nodal point in said inductance for effecting grid excitation of the succeeding electron tube from a point in said inductance below said nodal point, whilst securing balanced operation of said circuits from a point above the nodal point in said inductance.

3. An amplification system comprising a plurality of electron tubes each having grid, filament and plate circuits, the output circuit of one electron tube having two parallel branches, one of said branches comprising a capacity and the other branch comprising an inductance and capacity in series, said last named capacity providing a nodal point of voltage intermediate the ends of said inductance, a connection from said inductance on one side of said nodal point to the grid of a succeeding electron tube and a connection from said inductance on the opposite side of said nodal point through a capacity to the plate circuit of said succeeding electron tube.

4. An amplification system comprising a plurality of electron tubes each having grid, filament and plate circuits, the output circuit of one electron tube having two parallel branches, one of said branches com-

prising a variable capacity and the other branch comprising a variable inductance and a variable capacity in series, said last named capacity providing a nodal point of
5 voltage intermediate the ends of said inductance, a connection from said inductance on one side of said nodal point to the grid of a succeeding electron tube and a connection from said inductance on the opposite side
10 of said nodal point through a variable capacity to the plate circuit of said succeeding electron tube, whereby said last named capacity stabilizes said circuits.
